UNITED STATES PATENT OFFICE.

HANS R. SETZ, OF HIGHLAND PARK, PENNSYLVANIA; BERTHA E. SETZ ADMINISTRATRIX OF HANS R. SETZ, DECEASED.

SCAVENGING PORT FOR INTERNAL-COMBUSTION ENGINES.

Application filed August 16, 1924. Serial No. 732,430.

My invention relates to an improvement in internal combustion engines and more particularly to engines of the Diesel type.

In internal combustion engines of the Diesel type working on the two cycle principle, the matter of effectively scavenging the cylinders after the power stroke has always presented a serious problem and one which, though attacked from various angles, has not heretofore been wholly solved.

In well known forms of Diesel type engines, the scavenging of the cylinders is most effectively accomplished by the introduction of air under pressure into the cylinder after the exhaust has been opened and the major portion of the gases of combustion allowed to escape. In practice, the air is admitted to the cylinders through scavenging ports at one side of the cylinders and passes out of the cylinders through the exhaust located on the opposite side of the cylinders, theoretically sweeping out of the cylinders all of the gases of combustion not initially exhausted on the opening of the exhaust.

The present practice in scavenging while substantially effective leaves much to be desired and in fact fails to wholly clean out of the cylinders all of the gases of combustion, with the result that the new charge is to a certain extent contaminated by gases of combustion and the efficiency of the engine reduced.

Now it is the object of my invention to provide a novel construction of scavenging port, applicable to the Diesel type internal combustion engine, and whereby the scavenging air will be guided on its entry into the cylinder in such a manner as to cause it to so travel in the cylinder as to insure the most complete scavenging through the exhaust.

Having now indicated, in a general way, the nature, purpose and advantage of my invention, I will proceed to a detailed description thereof, with reference to the accompanying drawings in which I have illustrated a preferred embodiment, and in which the figure is a vertical section through an engine cylinder embodying my invention.

In the drawing, A indicates the working cylinder supported on a frame B, and C a

piston in the cylinder, shown in lower dead center position. D indicates an exhaust port positioned oppositely to a scavenging port E, the upper and lower walls of which are flared upwardly and downwardly respectively adjacent the interior of the cylinder A, and which provides a passage for air from an air receiver F to the interior of the cylinder. The scavenging port is divided into three passages a, b and c by means of guide vanes G and H, which conform respectively to the contour of the upper and lower walls of the port and terminate at a distance, preferably less than the width of the passages between the vanes and the walls of the port, from the cylinder bore.

By virtue of the provision of the guide vanes G and H in the scavenging port, it will be noted that the scavenging air from the receiver will pass through the scavenging port and toward the cylinder in three separate streams, each of the streams having a definite direction. Further, it is to be noted that since the pressure drop in the scavenging port is comparatively small, each of the air streams attain its maximum velocity at the narrowest section of the passages through which the streams respectively pass.

Thus, the air stream passing through the passage a attains its maximum velocity in the section a' and enters the cylinder in a line parallel to the contour of the upper wall of the port, or at an acute angle to the axis of the cylinder toward the top thereof. The air stream passing through passage b attains its maximum velocity in the section b' in which section its flow is in a line normal to the cylinder axis and with the piston in lower dead center position would tend to pass straight across the cylinder bore and into the exhaust. With the piston in any position above lower dead center and not closing the scavenging port, for example, as indicated by dotted line c', this stream would be caused to deviate in an upward direction by the wall of the piston.

The air stream passing through passage c will attain its maximum velocity in the section c' in a direction of travel parallel to and alongside of piston c, which causes it to impinge within the confines of the port on

the air stream from passage *b* at an angle of ninety degrees. Since the vanes *G* and *H* in following the contour of the upper and lower port walls form a divergent orifice in the plane where the air stream from passage *c* impinges upon the stream from passage *b* the direction of the stream from passage *b* is readily influenced by the stream from passage *c*, with the result that the united 10 streams flow into the cylinder in a direction toward the top thereof, more or less parallel to the stream from passage *a*. The upward deflection of the stream from passages *b* and *c* will be increased in the higher positions of 15 the piston to such an extent that in the higher positions of the piston, leaving the port open, the combined streams from passages *b* and *c* will cause the stream from passage *a* to be deflected and travel with a 20 steeper inclination toward the cylinder top.

It will now be clear that by virtue of my invention a scavenging port structure is provided which will insure the delivery of the scavenging air to the cylinder in a direction 25 toward the top of the cylinder, thus insuring substantially complete circulation of the scavenging air throughout the cylinder with resultant increase in efficiency of the scavenging.

30 It will be noted that though I have described an embodiment of my invention in detail, I do not intend that my invention be limited to the embodiment described, since it is capable of variations without departing from the invention.

Further, while the attached drawing refers to a single acting cylinder, the application of my invention is not understood to be restricted to single acting engines only, 40 but can with equal facility be used also on double acting engines.

Having now fully described my invention, what I claim and desire to protect by Letters Patent is:

45 1. In an internal combustion engine having a working cylinder, a scavenging port opening into the cylinder, and means whereby the scavenging air is divided in the port into a plurality of divergent streams and 50 is recombined therein to flow therefrom in a direction toward the top of the cylinder on the initial opening of the port.

55 2. In an internal combustion engine having a working cylinder and a piston therein, a scavenging port opening into the cylinder, means in said port whereby the scavenging air is divided and directed into divergent streams therein, said piston being adapted when the port is partially opened to divert 60 one of said streams into another and cause all of the scavenging air to flow into the engine cylinder in a direction toward the top thereof.

65 3. In an internal combustion engine having a working cylinder and a piston therein, a

scavenging port opening into the cylinder, and a vane in said port terminating short of the cylinder bore, said vane being adapted to divide the scavenging air within said port into streams, direct a stream of air 70 downwardly to impinge on the piston and be diverted thereby upwardly to impinge on another stream of air within said port when said port is partially opened.

4. In an internal combustion engine having 75 a working cylinder, a scavenging port opening into the cylinder, the upper and lower walls of said port being divergent from a point adjacent the cylinder bore, spaced 80 vanes conforming respectively to the contour of the upper and lower walls of said port and terminating at points spaced from the cylinder bore.

5. In an internal combustion engine having 85 a cylinder, a divergent scavenging port having divergent walls opening into said cylinder, vanes dividing said port into separate passages through which the scavenging air passes in individual streams, said pistons being adapted to cause one of said streams of air to impinge upon another stream and cause all the scavenging air to flow into the cylinder in a direction toward the top thereof when the port is partially opened.

90 6. In an internal combustion engine having 95 a working cylinder and a piston therein, a scavenging port opening into the cylinder at points above and below the lower dead center position of the piston, guide vanes within the port and terminating short of the inner end thereof whereby the scavenging air is divided into a plurality of streams, said guide vanes being so positioned as to cause one of said streams to travel upwardly and one of said streams to travel downwardly and to impinge on the piston trunk and diverted thereby to impinge on the other streams within the port and cause all the scavenging air to travel toward the top 100 of the cylinder on its entry therein.

105 7. In an internal combustion engine having 110 a working cylinder, a scavenging port opening into the cylinder, and means whereby the scavenging air is divided within the port into a plurality of streams and is recombined therein at a point adjacent the cylinder bore to flow therefrom in a direction toward the top of the cylinder when the port is open.

115 8. In an internal combustion engine having 120 a working cylinder, a scavenging port opening into the cylinder and means extending within the port and terminating short of the cylinder bore whereby the scavenging air is divided into streams within the port and permitted to recombine therein at a point adjacent the cylinder bore and before its entry into the cylinder.

125 9. In an internal combustion engine having 130 a working cylinder and a piston therein, a

scavenging port opening into the cylinder stream at a point adjacent the cylinder bore and a vane extending within the port and before the latter streams enter the cylinder. 10

whereby the scavenging air is divided into streams within the port, one of which will impinge on the piston and diverted thereby will be permitted to impinge on another

In testimony of which invention, I have hereunto set my hand at Chester, Penna., on this 12th day of August, 1924.

HANS R. SETZ.
